UNITED STATES PATENT OFFICE.

HOWARD MADISON PIERCE, OF BROOKLYN, NEW YORK, ASSIGNOR TO A. G. SPALDING & BROS., OF NEW YORK, N. Y., A CORPORATION OF NEW JERSEY.

GOLF BAG.

Application filed September 22, 1920. Serial No. 411,918.

To all whom it may concern:

Be it known that I, HOWARD M. PIERCE, a citizen of the United States, residing in the borough of Brooklyn of the city of New York, in the State of New York, have invented certain new and useful Improvements in Golf Bags, of which the following is a specification, reference being had to the accompanying drawing, forming a part 10 hereof.

This invention relates to an improved golf bag designed particularly for use by a golfer who plays without the services of a caddy. A player without a caddy drops his 15 bag on the ground at full length while making a stroke and after completing the stroke must return to the bag and pick it up before proceeding. This is not only tedious but often results in the taking of a few steps 20 before the bag is remembered and invariably necessitates taking the eye from the point where the ball is marked at rest. Further, in dropping the bag on the ground in this manner, the bag becomes damaged and the 25 club shafts often have injurious strains imposed upon them sufficient to give them a slight set. Bags of the usual type are formed with stiffening stays sewed in pockets and extending lengthwise of the body of 30 the bag while usually some sort of a stiff base or reinforced section is provided at the bottom to support the clubs and support the bag. In accordance with the present invention it is proposed to provide a bag which 35 shall be substantially in all respects similar to the common type of reinforced bag, but which shall have incorporated therein means for holding it upright when rested on the ground. With the bag thus held in upright 40 position a player can golf without a caddy with convenience, the act of resting the bag on the ground serving to secure it in vertical position. With the bag in vertical position its handle can be grasped readily 45 after the stroke is completed, the eye can be kept on the ball after it comes to rest and neither the bag nor the clubs will be subjected to the wear and strains imposed by throwing them carelessly on the ground. 50 The improvements are realized in the illustrated embodiment by extending the stiffening stays of the bag through the bottom thereof and preferably forming them at their lower ends as prongs which will readily enter the ground when the bag is set on 55 end. These prongs are of such number and relationship as to hold the bag vertically and yet permit it to be raised from the ground without undue effort. Further, the stays with the prongs are preferably of less 60 length than the over-all length of the bag, so that when the latter is rested on a hard surface the usual base of the bag will be in contact therewith.

A further general object of the invention 65 is to provide a bag of the character described which shall be simple in construction and inexpensive to manufacture, the changes from the present day type of bag being of such simple character as to permit them to 70 be readily incorporated therein.

The invention will be described in detail with reference to the accompanying drawing in which is illustrated one suitable embodiment of the invention. In the drawing—

Figure 1 is a view in elevation of a bag provided with the improved prongs.

Figure 2 is a fragmentary sectional view on a somewhat larger scale taken through 80 the lower end of the bag shown in Figure 1 and on the plane indicated by the line 2—2 of Figure 3 and looking in the direction of the arrows.

Figure 3 is a horizontal sectional view 85 taken on the plane indicated by the line 3—3 of Figure 1 and looking in the direction of the arrows.

The invention is not concerned with the character of the body *a* of the bag, this 90 body being made as usual, of any suitable materials and dimensions and usually formed at the lower end with a base section *a'* of extra plies of material, this base section being usually of some degree of stiffness, so as to afford suitable support for the bag when placed on the unyielding surface. The body of the bag is reinforced longitudinally by stays *b*, usually three in number, retained in place in any suitable way, as by 100 stiffened pocket strips *b'*. It is the usual practise to extend the stays *b* from end to end of the bag and secure them throughout their length to the wall thereof. In the preferred embodiment of the present invention 105 it is proposed to have these stays *b* perform a dual function by extending them through the bottom wall *a'* of the bag and forming their ends as prongs *b*² which may enter the earth. In attaining this object, and as 110

shown very clearly in Figure 2, the retaining pocket strips b' will terminate somewhat above the base a' of the bag and the stays b will extend through openings a^3 formed in the folds in which said stays rest, these openings a^3 being also placed at some little distance above the base a' . The result of this construction is that the section of the bag between the base a' and the holes a^3 is flexible and is not reinforced, so that the material shown at a^4 can move readily into folds as the prongs b^2 enter the ground, the base a' of the bag resting meanwhile on the surface of the turf. It is not understood from the foregoing description, however, that the invention is limited to the precise method of incorporating the stays b in the wall of the bag a nor to the precise relationship existing between the strips b' , the holes a^3 and the base a' , since it is evident that other constructions, many of which are already in use, can be employed for the purpose of securing the stays to the bag. Nor is it to be understood that the reinforcing stays b need actually be formed as prongs b^2 for the purpose specified, since it is evident that such prongs to serve the same function might be made separate from the stays although it is not considered that such construction would possess all the manufacturing advantages attributable to the illustrated form.

In use, it will be apparent that when the bag is supported from its upper end the base a' will extend downwardly over the lower ends of the prongs b^2 and the bag in this condition can be rested on an unyield-

ing surface without exposing the prongs. When the bag is rested on turf, however, it will be evident that with the base a' resting 40 on the surface thereof the prongs b^2 will continue downwardly into the earth while the bag buckles at a^4 . The prongs are of such number and disposition as to retain the bag in its vertical position when so set, 45 although it is evident that when the player moves the bag from the ground, the prongs will be withdrawn from the earth without difficulty. The advantages of this construction when playing without a caddy have 50 been pointed out in the preamble, but of course, the invention is not to be limited to the uses thereof.

I claim as my invention:

In a golf bag of flexible material, a set 55 of three pointed stays fixed to the top of the bag and extending longitudinally thereof on the outside of the wall of the bag to a point above the lower end where they enter through openings in the wall into 60 the interior of the bag, said stays lying normally between the ends of the bag, stiffened pocket strips sewed over the stays to inclose their exposed portions, a stiff base section having openings in its bottom wall, 65 and a collapsible section between the lowermost ends of the pocket strips and the base section to permit buckling of the bag and entrance of the pointed stays into the ground by pressing on the top of the bag. 70

This specification signed this 21st day of Sept., A. D. 1920.

HOWARD MADISON PIERCE.
